(57) **CLAIM**

The ornamental design for a dental tool, as shown and described.

DESCRIPTION

FIG. 1 is a perspective view of a dental tool showing our new design;

FIG. 2 is a right side elevational view with the left side being a mirror image thereof;

FIG. 3 is a top view with the bottom view being a mirror image thereof;

FIG. 4 is a front elevational view thereof;

FIG. 5 is a rear elevational view thereof; and,

FIG. 6 is an environmental perspective view thereof.

The broken line showing of the wire and teeth is for the purpose of illustrating environmental structure and forms no part of the claimed design.
